UNITED STATES PATENT OFFICE

135,601

DESIGN FOR A MATERNITY AND ABDOMINAL SUPPORTING GARTER BELT

Olga Erteszek, Los Angeles, Calif.

Application October 21, 1942, Serial No. 108,588

Term of patent 7 years

To all whom it may concern:

Be it known that I, Olga Erteszek, a citizen of Poland, residing in Los Angeles, in the county of Los Angeles and State of California, have invented a new, original, and ornamental Design for a Maternity and Abdominal Supporting Garter Belt, of which the following is a specification, reference being had to the accompanying drawing, forming a part thereof.

Fig. 1 is a front elevational view of a maternity and abdominal supporting garter belt showing my new design,

Fig. 2 is a rear elevational view thereof, and
Fig. 3 is a side elevational view thereof.

I claim:

The ornamental design for a maternity and abdominal supporting garter belt, as shown.

OLGA ERTESZEK.
